Claims priority, application France May 10, 1958

4 Claims. (Cl. 74—477)

This invention relates to forks of the type utilized for controlling the movements of sliding gears in gearboxes and the like, and has specific reference to a particularly simple and economical structure and construction of a two-fork arrangement applicable to the control of two sliding gears or like members.

According to the essential feature of this invention, the two forks are of the type sliding on a fixed rod and consist of pressed and bent sheet-metal elements so as to form notably, in addition to the fork-shaped side controlling the sliding gear corresponding to each of them and when observing said forks in plane view, two opposed and interengaging U portions slidably mounted by their outer arms on said fixed rod, the inner arms of these U portions being formed with corresponding pressed registering detent-positioning notches adapted to co-act with a single locking and safety device carried by the same rod.

In order to afford a clearer understanding of this invention and of the manner in which the same may be carried out in the practice, reference will now be made to the accompanying drawing forming part of this specification and illustrating diagrammatically by way of example a typical form of embodiment thereof. In the drawing:

Figure 1 shows in elevational view taken in a direction at right angles to the guide rod two forks mounted thereon;

Figure 2 is a plane view from above showing the arrangement of Fig. 1, and

Figure 3 is a cross-sectional view taken upon the line III—III of Fig. 1.

In the drawing, the reference numerals 1 and 2 designate two forks of pressed and bent sheet metal which are mounted according to this invention on a fixed rod 3.

As shown in Fig. 2 these two forks constitute two opposed interengaging U portions mounted for sliding movement on the rod 3 by means of the outer arms partially surrounding this rod and designated by the reference numerals 4 and 5, respectively. The central or inner arms of these U portions are each formed with three registering pressed detent-positioning notches 6 adapted to co-act with a single locking and safety device 7 carried by the rod.

Each fork is formed with an opposite gear-engaging forked portion 8, 9 adapted to co-act with the corresponding sliding gear or like member of the gearbox. These gear-engaging forks are conveniently co-extensive with one arm of the U, the proper disposition being subordinate, as a matter of fact, to the position of the sliding gears or like members in the gearbox.

Moreover, the central or inner arms of the aforesaid interengaging U-shaped portions are formed at their top with notched and bent registering extensions providing together an aperture 10 adapted to receive the driving end of a fork-actuating control lever (not shown).

As will be readily understood, the locking and safety device 7 consists simply of a pair of opposite spring-loaded bolts 11 slidably mounted in a guide sleeve 12 fitted in a transverse bore of the rod 3, these bolts being urged against the detent positioning notches 6 by a common central compression spring 13.

2

The safety feature, which consists in preventing the two forks from moving simultaneously in case of improper positioning of the control lever (not shown) engaging the aforesaid aperture 10, is obtained by forming the spring-loaded bolts 11 with such axial dimensions that their combined length exceeds that affording the simultaneous clearing of the ridges 14 separating adjacent notches 6 by these bolts; in other words, this length must be greater than the distance 15 measured between a pair of registering ridges 14 across the rod 3.

The safety obtained against the untimely or undesired displacement of a fork member either as a consequence of the inertia of the sliding gear, or for any other reason, while the other fork is in a speed-engaging position, results from a difference in depth between the central notch 6¹ and the lateral notches, the former being deeper than the latter. Thus, for example, assuming that the fork 9 has been moved to a position corresponding to the engagement of a relevant gear, one end notch 6 will register with the locking and safety device 7 and the distance measured between the inner faces of the spring-loaded bolts is therefore inferior to that existing between the bottom of the opposite notch 6¹ and the ridges 14, whereby the other fork 8 is safely held against movement.

In addition to the action resulting from the presence of this detent-positioning and safety device, the forks are also maintained in their proper relative positions about the rod 3 by the engagement of their fork-shaped portions 8 with the relevant sliding gear or like member.

I claim:

1. A gearbox fork arrangement for controlling two sliding gears comprising a stationary rod, a pair of forks mounted to slide axially on the rod and having gear engaging projecting portions, said forks being formed from pressed and bent sheet metal and including opposed interengaging U-shaped portions, each portion having outer arms slidably mounted on the rod and inner arms having inner opposing faces formed with corresponding pressed, registering detent-positioning notches and a single locking and safety device carried by the rod with which the notches coact.

2. A gearbox fork arrangement as defined in claim 1, wherein the inner arms are formed at their top with notched and bent registering extensions forming together an aperture adapted to receive the driving end of a fork-actuating control lever.

3. A gearbox fork arrangement as defined in claim 1, wherein said locking and safety device consists of a pair of opposed spring-loaded bolts slidably mounted in said rod and extending radially therefrom and urged for engagement with the detent-positioning notches by a common spring interposed between said bolts, the axial dimensions of said bolts being such that their combined length exceeds that affording the simultaneous clearing by these bolts of the opposite ridges that separate the adjacent detent-positioning notches.

4. A gearbox fork arrangement as defined in claim 3, wherein any undesired displacement of one fork while the other fork is in the proper gear engaging position is prevented by forming the end notches with a depth less than that of the intermediate notch whereby the distance measured between the inner faces and the spring-loaded bolts is less than depth of the intermediate notches.
